THUMB REST FOR FLATIRONS

Ambrose D. Olds, Wichita, Kans., assignor to The
Coleman Lamp and Stove Company, Wichita,
Kans., a corporation of Kansas

Application November 20, 1933, Serial No. 698,837

6 Claims. (Cl. 68—26)

This invention relates to flat irons and primarily to a thumb rest. The invention is especially designed for use in connection with electrically heated flat irons but obviously it is capable 5 of being used with any type flat irons. The principal object of the invention is to provide an improved grip for the iron, by conveniently locating a thumb rest with relation to the main handle or grip, the thumb rest being adjustable to suit 10 different operators and it is so co-related with the main grip or handle that it can be adjusted for either a right or left handed person as well as persons with different hand characteristics. Hands differ in shape, size, etc., so a rigid thumb 15 rest which would conveniently accommodate one person would be unsuitable for another, consequently, I have provided means whereby a wide latitude of adjustment is capable of accommodating different personal requirements.

20 The novelty of the invention will be clearly understood by reference to the following description in connection with the accompanying drawing in which:

Figure 1 is a side elevational view of an iron 25 to which my invention is applied.

Figure 2 is a top plan view of an iron to which my invention is applied, the thumb rest being shown in full line position for a right handed operator and dotted line position for a left handed 30 person, the handle being shown partly in section.

Figure 3 is a front view of the thumb rest, the handle and part of the handle bow, and

Figure 4 is a disassociated view of part of the 35 bolt, one end of the bow, the thumb rest and the front end of the handle.

Referring now to the drawing by numerals of reference: 1 designates the main body of the iron which may be of any approved construction 40 provided with a handle bow 2, having the up-standing ends 3 and 4 to which the handle 5 is secured by a bolt 6 passing thru the upper ends of the bow members 3 and 4, and thru the handle. The front bow member 3 is provided with a rectangular opening 7, to receive the rectangular portion 8 on the bolt 6, so that the bolt will be held against rotation to enable the nut 9 on the end of the bolt in the recess 10 of the handle to be turned to release the bolt or to tighten it. The handle 5 is provided with a reduced or constricted portion 11 to be received in the recess 12 of the head 13 of the thumb rest. The head 13 is provided with a notched face 14 to receive the detent 55 or pawl 15 on the front bow member 3. The head

13 is provided with an outstanding thumb receiving seat 16.

It will be apparent that when the parts are in opposite position, it will be necessary only to loosen the nut 9 on the bolt 6 so as to withdraw 5 the detent 15 from the notched face 14 of the head 13 so that the thumb rest can be rotated or turned on the constricted portion 11 of the handle, so as to locate the seat 16 in proper position to accommodate the person using the iron, 10 then the nut 9 can be tightened on the bolt to set the parts in the desired position. The thumb rest can be swung thru a considerable arc from right to left and vice versa so that it can be adjusted for either a right handed or left handed 15 person or any angle between two extremes. The flexibility of the adjustment is an important feature of my invention so I do not wish to be limited to the exact detail of construction shown in the preferred embodiment thereof. 20

What I claim is:

1. In a flat iron, a body, a handle, a bow supporting the handle, a thumb rest at the front end of the bow mounted to swing in an arc about the axis of the handle and means for holding the 25 thumb rest rigid with respect to the handle in any of a plurality of positions with respect to the handle.

2. In a flat iron, a body, a handle, means for connecting the handle to the body in spaced 30 relation therewith, a reversible thumb rest associated with the handle movable about the axis of the handle and means for holding the thumb rest, in any of a number of positions between two extremes, rigid with respect to the handle. 35

3. In a flat iron having a handle above the body of the iron a reversible thumb rest mounted to swing about the longitudinal axis of the handle from one side of a vertical plane passing through said axis to the opposite side of the vertical plane and vice versa, and means for holding the thumb rest rigid in either of its two positions. 40

4. In a flat iron having a handle support above the body and secured thereto, a reversible thumb rest carried by the support for the handle and 45 having a part with detent engaging notches said thumb rest being supported to swing about the longitudinal axis of the handle in a clockwise and counterclockwise direction and a detent to engage the notches to hold the thumb rest rigid. 50

5. In a flat iron, a body, a handle, a bow having up-standing arms, a bolt extending through the up-standing arms and through the handle to support it, a thumb rest having swinging movement about the axis of the bolt independent of the 55

handle and provided with a roughened face and a detent on the front arm of the bow to engage the roughened face of the thumb rest, whereby the thumb rest will be held rigid against swinging movement.

6. In a flat iron, a body, a handle, a bow supporting the handle, a reversible thumb rest at

the front end of the bow mounted to swing in an arc independent of the handle and means for holding the thumb rest rigid with respect to the handle in any of a plurality of positions between two extreme positions.

AMBROSE D. OLDS.
